UNITED STATES PATENT OFFICE.

JUSTIN WHITNEY, OF BOSTON, MASSACHUSETTS.

IMPROVEMENT IN UPRIGHT-PIANO FRAMES.

Specification forming part of Letters Patent No. 123,212, dated January 30, 1872.

Specification describing certain Improvements in Metallic Frames for Upright Pianos, invented by JUSTIN WHITNEY, of Boston, in the county of Suffolk and State of Massachusetts.

The invention will first be fully described and then clearly pointed out in the claim.

In the accompanying drawing, Figure 1 represents a front view of the frame. Fig. 2 is a vertical section of Fig. 1 on the line x x . Fig. 3 is a horizontal section of Fig. 1 taken on the line y y . Fig. 4 is a cross-section of one of the trusses taken on the line z z , Fig. 1.

Similar letters of reference indicate corresponding parts.

A is the frame, which stands upright, as seen in the drawing, and forms the back, which supports the strings of the instrument, the strings being drawn across it over the bridge and sounding-board. The sides B B and bottom C of the frame are made in double angle-iron form, and the trusses D are of iron in the form of double T's in cross-section, as seen in

the drawing. The top E is of irregular form, the front portion F being the bridge, over which the strings pass.

Like some other parts of pianos—the legs, for instance, for square or horizontal pianos—these frames are made for the "trade" and sold as an article of commerce, the form or size of the frames being varied to suit different piano-manufacturers.

Having thus described my invention, I claim as new and desire to secure by Letters Patent—

As an article of manufacture, an upright iron frame, A, made in one piece by casting the sides B, bottom C, trusses D, top E, and bridge F in the form shown and described.

The above specification of my invention signed by me this 4th day of October, 1871.

JUSTIN WHITNEY.
